AIR TRANSLATING APPARATUS SUPPORT

**Gustav H. Koch, Springfield, Mass., assignor to
Westinghouse Electric Corporation, East Pitts-
burgh, Pa., a corporation of Pennsylvania.**

Application March 13, 1947, Serial No. 734,516

5 Claims. (Cl. 248—194)

1

This invention relates to electric fans, and more particularly to a fan of the type supported on an adjustable floor standard or frame.

It is an object of the present invention to provide an improved floor fan assembly having an adjustable frame or standard of tubular construction.

Another object of the invention is the provision of an improved floor fan assembly having telescopic means which provide minimum height in the low or collapsed position in order to reduce the space occupied and thus to facilitate shipping of the assembly.

A further object of the invention is the provision, in a floor fan assembly, of a standard of tubular construction including relatively movable telescoping elements equipped with clamping means to hold them in extended position; and concealed means for limiting extension of the tubular standard assembly beyond a safe position.

It is also an object of the invention to provide an improved floor fan having the desirable characteristics and features already described, and which is so devised as to require a relatively small number of simple and inexpensive parts which may readily be assembled to form a durable product of light-weight construction.

Other objects and advantages of the invention will appear in the following more detailed description thereof taken in connection with the accompanying drawings in which:

Fig. 1 is an elevational rear view of a floor fan assembly constructed in accordance with the invention.

Fig. 2 is an elevational rear view showing the rear face of Fig. 1 in its longitudinal section.

Fig. 3 is an elevational side view of the floor fan of Fig. 1 in its low or collapsed position;

Fig. 4 is an enlarged detail fragmentary view of one leg of the frame or standard with the ad-

justable members thereof shown in section; and Fig. 5 is an elevational view of the upper frame section of the floor fan assembly shown in Fig. 1, illustrating the normally concealed position-limiting means associated therewith.

Referring to Figs. 1, 2 and 3 of the drawings, the improved floor fan assembly comprises an electrically-driven fan unit indicated generally by the reference character 1, which is suitably supported within a shroud assembly 2 carried by an inverted U-shaped tubular frame section 3 having vertically-disposed portions 4 mounted in telescoping relation on the upwardly-extending legs 5 of a base frame section 6.

The frame section 6 is adapted to rest on the

(Cl. 248—194)

2. The apparatus support of claim 1, wherein the base frame section 6 has a forwardly-extending horizontal portion 7 adapted to rest on the floor in front of the corresponding leg 5, and further bent outwardly and then rearwardly to terminate in an elevated inwardly-extending end 8, on which a roller wheel 9 is journaled. The two inwardly-bent ends 8 are aligned and spaced apart by a tubular element 10, so that the roller wheels 9 are thus mounted in parallel relation rearwardly of the vertical legs 5, which are normally given forward support by the tubular portions 7. In order to impart rigidity to the base frame section 6, V-shaped struts 10a are interposed between and welded to the lower ends of the legs 5 and the respective elevated ends 8 carrying the rollers 9.

The upper frame section 3 is formed of metal tubing of a larger size than that employed in the base frame section 6. I prefer to utilize a single tubular member bent in the form of a U to provide the normally vertically-disposed portions 4, the intermediate portion 11 being adapted to extend above the shroud assembly 2 containing fan 1, thus providing a convenient handle. The lower end of each portion 4 is provided with one of a pair of clamping devices 12 and is mounted in adjustable telescoping relation with the corresponding vertical leg 5 of the base frame section 6.

Referring now to Fig. 4 of the drawings, where in one of the clamping devices 12 is illustrated in enlarged detail, it will be seen that the tubular portion 4 of the upper frame section 3 is of sufficient diameter to receive the associated tubular leg 5 in telescoping relation while providing sufficient clearance to allow a non-metallic tubular element 13, preferably made of relatively soft fibrous or plastic material, to be interposed between the telescoped frame members. The lower end of tubular portion 4 has fitted thereon an annular member or collar 14 which has a shoulder 15 formed on the lower portion thereof for holding the fibrous tube 13 in place within the tubular portion 4. Suitable means may be provided for securing the collar 14 to the lower end of tubular portion 4, including an adjustable screw element 16 disposed in a threaded bore 17 and having an inner end 18 adapted to extend through an opening 19 formed in the tubular portion 4. Interposed between the portions of the tubular member 4 and tube 13 adjacent the collar 14 is a split annular spring element 20, the ends of which are

spaced to receive the end 18 of the screw 16 therebetween. A manual clamping member 21 having a handle 22 is mounted in screw-threaded relation in a suitable bore formed in collar 14 opposite the bore 17, and is adapted to be tightened into confining engagement with the annular spring element 20 for causing the latter to force the adjacent portion of tube 13 into gripping relation with the outer surface of leg 5. It will thus be seen that each clamping device 12 is adapted to hold the related tubular portion 4 of the upper frame section 3 in any desired position, with respect to the associated leg 5 of the frame section 6, without marring or otherwise damaging the surface finish of the latter, by reason of the fact that the non-metallic sleeve 13 is utilized to avoid metal-to-metal contact between the telescoped members.

In order to prevent upward movement of the frame section 3 beyond its uppermost position as illustrated in Fig. 1, the floor fan assembly is provided with a concealed stop or position-limiting means, which, in the preferred embodiment of the invention illustrated in Figs. 4 and 5 of the drawings, comprises a looped flexible wire or cable 23, which is contained within the U-shaped tubular frame section 3. In order to insure against the possibility of noisy contact between the wire 23 and an inner surface of frame section 3, the wire 23 is preferably provided with a suitable covering 23a, which may be in the form of wound cotton thread. As shown in Fig. 5, one looped portion of wire 23 projects downwardly beyond one of the tubular portions 4 of the tubular frame section 3, and the two joined ends of the wire extending outwardly of the other portion 4 are secured together by means of a clamping ring 24, best shown in Fig. 4. It will be noted that the ends of the wire 23 are bent upwardly and clamped to the ring 24, and preferably soldered into place. At a point near the upper end of each of the tubular legs 5 of the base frame section 6, the opposite surfaces of the leg are provided with indented and apertured surfaces 25 for receiving a pair of complementary screw-threaded elements 26 and 27 forming a sleeve-nut assembly which is adapted to be fitted transversely within tubular leg 5 to form an anchor for the adjacent end of looped wire 23. It will be apparent that when the members of the frame structure are assembled as shown in Fig. 4, excessive upward movement of the frame section 3 beyond a predetermined safe position with respect to frame section 6 will be prevented upon engagement of the ends of looped wire 23 with the respective pairs of sleeve-nut elements 26 and 27 carried in legs 5.

In order to assemble frame sections 3 and 6, the looped end of the wire 23 may first be inserted into one of the tubular portions 4 and drawn outwardly of the other tubular portion so that the ends of the wire 23 secured by ring 24 will also project from the first tubular portion 4, as shown in Fig. 5 of the drawings. The tubular portions 4 are then brought into telescoped relation with the legs 5 of the lower frame section 6, whereupon the respective pairs of screw-threaded elements 26 and 27 may be inserted through the apertures in the indented surfaces 25 of the legs 5 and through the corresponding loops of the wire 23. It will be understood that the opposite looped ends of wire 23 are thus positioned about the respective pairs of elements 26 and 27, so that they will simultaneously be brought into engagement with these elements to prevent movement of the upper frame section 3.

beyond its uppermost position. By slidably mounting within the U-shaped frame section 3 a single wire 23, doubled as described to provide looped ends that are inherently equalized in length, simultaneous engagement of both looped ends with the respective pairs of elements 26 and 27 is insured. This feature of the invention provides a considerable advantage over the use of separate and independent stop means for each of the two sides of the frame section.

It will thus be seen that the improved floor fan assembly just described may be adjusted to a maximum height, or a maximum dimension A as indicated in Fig. 1 of the drawings, in which position only the uppermost portions of tubular legs 5 of the base section 6 still remain in telescoping relation with the lowermost ends of the tubular portions 4 of the upper frame section 3. The height of the fan unit and the surrounding shroud assembly 2 constitutes a part of the dimension A. Referring to Fig. 2, it will be observed that upon adjustment of the standard of the fan assembly to its telescoped or collapsed position, indicated by dimension B, the height of, and, therefore, the space occupied by, the entire floor fan assembly is substantially halved, due to the fact that the tubular legs 5 are received in the tubular portions 4 of the upper frame section through a distance which includes the height of the fan unit 1 and surrounding shroud assembly 2. The fan assembly in its collapsed position as shown in Fig. 2 may thus be more readily handled for shipping and other purposes than would be the case with a frame standard of the type heretofore employed, having telescoping means permitting overlapping of only the portions of the frame members located below the fan unit and shroud assembly, whereby only the dimension of the standard below the fan unit could be halved. From the foregoing it will be apparent that the improved floor fan assembly constructed in accordance with the invention will present unmarred exterior surfaces and a decorative appearance regardless of the position to which the upper frame section may be adjusted. The tubular construction of the frame members together with substantial concealment of otherwise unsightly elements of the necessary clamping and position-limiting mechanisms are desirable characteristics rendering the fan apparatus suitable for household use. By reason of the provision of hidden sleeves or tubes of non-abrasive material as elements of the clamping mechanisms, any number of adjustments of the fan standard may be made without materially affecting enameled or other highly finished surfaces. By using the novel and inexpensive arrangement of the wire loop contained in the U-shaped section in cooperation with the stationary stop elements carried in the floor or base section, the standard assembly has been rendered substantially fool-proof without unduly complicated additional structural elements.

It will further be obvious that convenience in use and ease of transportation of the floor fan are insured by the proportioning, construction and arrangement of the upper and lower tubular frame members as herein disclosed, facilitating lowering of the assembly from its maximum height to an extremely compact or collapsed position, wherein the top of the fan unit is brought closely adjacent the uppermost ends of the tubular standard or base members.

While I have shown my invention in but one form, it will be obvious to those skilled in the

art that it is not so limited, but is susceptible of various changes and modifications without departing from the spirit thereof.

Having now described my invention, what I claim as new and desire to secure by Letters Patent, is:

1. In an air translating device including a motor driven fan unit, a base frame including a vertically-disposed standard member, a tubular fan support member carrying said fan unit and having a portion slidably mounted in telescoping relation with said standard member, said fan support member being adjustable through a range of positions from a low position wherein the top of the fan unit is closely adjacent the top of said standard member and the latter overlaps substantially the entire vertical extent of the fan unit, to a high position wherein only minimum lengths of said members remain in telescoping relation.

2. In an air translating device including a motor driven fan unit, a base comprising a pair of vertically-disposed tubular standard members, a fan mount for carrying said fan unit comprising a pair of tubular portions disposed in telescoping relation with said tubular standard members, respectively, said fan mount being adjustable through a range of positions from a low position wherein the top of the fan unit is closely adjacent the tops of said standard members so that the vertical extent of said fan unit is substantially within the height of said standard members, to a high position wherein only minimum lengths of said standard members and tubular portions remain in telescoping relation, and locking means associated therewith for locking said fan mount in any selected position within said range of positions.

3. In an air translating device including a motor driven fan unit, a base including a vertically-disposed standard member, a tubular fan support member carrying said fan unit and having a portion slidably mounted in telescoping relation with said standard member, said fan support member being adjustable relative to said standard member through a range of positions from a low position wherein the top of said fan unit is closely adjacent the top of said standard member, to a high position wherein only predetermined minimum lengths of said members remain in telescoping relation, and means for preventing movement of said fan support member beyond said high position comprising a concealed doubled wire anchored in said fan support member and a stop element fixed in said standard member, said stop element being engageable

by said wire upon movement of said fan support member to said high position.

4. In an air translating apparatus including a motor driven fan unit and a housing assembly for supporting said fan unit, an adjustable floor frame assembly comprising a base section having a pair of vertically-disposed tubular standard members, a U-shaped tubular frame section carrying said housing assembly and having downwardly-extending portions mounted in telescoping relation with said standard members, respectively, holding means operative to hold said relatively movable telescoping members in an extended position, stationary stop elements secured to each of said tubular standard members, and a flexible wire element extending through said U-shaped tubular section and having looped ends cooperative with said stop elements for determining the uppermost position of the fan unit.

5. In an air translating apparatus including a motor driven fan unit and a housing assembly for supporting said fan unit, an adjustable floor frame assembly comprising a base section having a pair of vertically-disposed tubular standard members, a U-shaped tubular frame section carrying said housing assembly and having downwardly-extending portions mounted in telescoping relation with said standard members, respectively, clamping means operative to clamp said relatively movable telescoping members in any desired position, stationary stop elements secured to each of said tubular standard members, and means for limiting upward travel of said frame section including a doubled wire extending through said frame section, said wire being looped about both of said stop elements, the span of said wire being such as to bring the looped portions thereof into engagement with the respective stop elements upon movement of said fan unit to the uppermost position.
